UNITED STATES PATENT OFFICE.

JAMES E. JONES, OF COLUMBUS, OHIO.

RAIL-TIE.

1,207,558.

Specification of Letters Patent. Patented Dec. 5, 1916.

Application filed September 3, 1915, Serial No. 48,826. Renewed May 18, 1916. Serial No. 98,441.

To all whom it may concern:

Be it known that I, JAMES E. JONES, a citizen of the United States, residing at Columbus, in the county of Franklin and State of Ohio, have invented certain new and useful Improvements in Rail-Ties; and I do hereby declare the following to be a full, clear, and exact description of the invention, such as will enable others skilled in the art to which it appertains to make and use the same.

My invention relates to improvements in rail ties and resides in the provision of a metallic tie that will operate in a reliable manner to support the rails, which is simple as to construction, durable and inexpensive to manufacture.

Another object of importance is to provide a rail tie that is constructed and arranged to coöperate with novel rail clamping means forming a part of my invention so that the rails are securely held against creeping or spreading and may be readily laid or removed for the purpose of repair, without necessitating the removal of spikes or bolts or other fastening means similar thereto.

Another object is to generally improve rail ties and fastening means therefor so as to render them more practical, reliable and efficient in operation and inexpensive to manufacture.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a longitudinal vertical sectional view taken through my improved tie and showing the rail clamping means in side elevation and clamping rails in position, Fig. 2 is a top plan view of my improved tie with the fastening means removed, Fig. 3 is a transverse sectional view taken on line 3—3 of Fig. 1 and showing the means for adjustingly holding the movable clamping jaws in operative position, Fig. 4 is a detail perspective view of the wedge plate for adjusting the movable clamping jaws, Fig. 5 is a detail perspective view of one of the station-

ary rail clamping jaws, Fig. 6 is a detail perspective view of the movable rail clamping jaw, Fig. 7 is a detail plan view of the wedge pin, and Fig. 8 is a top plan view of the means to lock the wedge pin in position.

Referring to the drawings by characters of reference, the numeral 1 designates an elongated metallic body portion that is beveled upwardly as at 2 at its ends and provided with approximately triangular openings 3 at its ends, which openings extend from side to side of the body. The body portion 1 comprises a rectangular base plate 4 having formed at its ends and upon its upper side upstanding rail supporting portions 5 that are joined by means of a vertical rib 6 that is preferably formed integral with the body plate 4 and opposed faces of the rail supporting portions 2.

An angular opening 7 is formed centrally of the ends of the web. The provision of these openings 7 and 3 enables a skeleton construction which eliminates unnecessary waste in construction of the tie.

The web 6 is formed on its upper face with a longitudinal slot 8, the ends of which communicate with a recess 9 formed in each end of the tie in the rail supporting portions 4 thereof. On the inner faces of the outer walls of the recesses 9 and adjacent to the bottom walls of said recesses are formed relatively smaller recesses 10 for a purpose to be later more fully described.

Mounted within the recesses 9 are rail clamping jaws designated 11 as an entirety that are stationary and consist of base portions 12 formed with upstanding curved portions 13, the free ends of which are designed to engage the outer faces of the webs of the rails and upon the tops of the bases thereof. A lug 14 is formed on the rear edge of the base 12 of each of the members 11 and fits within the adjacent recess 10 thus holding the members 11 against upward movement relative to the tie. The recesses 9 are sufficiently deep that the main part of the rail clamping jaws 11 are disposed therein. Thus a secure fastening is provided and the rigidity of the tie in general is increased. Only the upper curved portions of the members 11 project above the surface of the tie. The recesses 9 are of such length as to enable the removal and ready insertion of the bases 12 and lugs 14 in position. The outer faces of the por-

tions 13 that are approximately vertical engage the inner faces of the outer walls of the recesses 9. The portions 13 are formed adjacent to the outer ends of the bases 12 thus providing an upper surface for the bases which surface is flush with the bottom of the slot 8 in the web 6 for a purpose to be later more fully described.

Mounted within the slot 8 are movable rail clamping jaws 15 each of which consists of an elongated approximately rectangular shank 16 that is formed adjacent to its outer end with an upwardly and outwardly curved rail engaging portion 17 to engage the rails in a manner similar to the portions 13. The portions 17 overlie the upper face of the shank 16 adjacent to the outer end of the shank so that the bases of the rails engage upon the upper faces 20 of the shanks adjacent the outer ends thereof. The under faces of the shanks adjacent to the outer ends thereof engage upon the upper faces of the bases 12 and in so doing securely hold the jaws 11 in position and provide a rigid support for the rails. The opposed inner ends of the shanks 16 are concaved as at 18 for a purpose as will be later more fully described. The outer ends of the shanks 16 extend into the recesses 9 as described and are normally arranged so as to be permitted slight movement toward the opposed faces of the portions 13 to effect a tightening of the clamping members of the tie.

As a means for moving the movable rail clamping jaws 15 into operative position relative to the rails I provide a relatively flat wedge plate 19 that is tapered toward one end and formed intermediate its ends with openings 20. The plate 19 is inserted between the opposed inner ends of the shanks 16 and at its side edges, engages the concaved faces 18 of said shanks, of greater length than the web 16 is wide and projects therebeyond on either side thereof, more on one side than the other so that the openings 20 are free from the top of the web. A wedge pin 21 is inserted through one of the openings 20 and upon one edge engages one face of the web so as to hold the plate 19 in position. As a means for holding the wedge pin 21 against slipping I provide a U-shaped clamping member 22 the arms of which are bent upwardly as at 23 and engage within a recess 24 formed in the under face of the web 16. The body portions of the arms and body portion of the member 22 extend outwardly from the web. The member 22 is preferably formed of spring metal so that the wedge pin 21 which when driven between the arms of the member 22 will cause the arms to expand. Any suitable means may be employed for supporting the member 22 while the wedge pin 21 is being driven into it. I provide

notches 24 on the wedge pin on opposite sides thereof which notches engage the arms and hold the member 22 against falling. It will be readily seen that the wedge pins 21 are held against accidental removal. By 79 moving the wedge plate 19 the clamping action may be adjusted to suit and the wedge pins 21 are then inserted through the desired opening 20 in the plate 19 and fastened in position as described.

It will be readily seen that I have provided a simple, inexpensive and reliable rail tie and fastening means therefor, that is durable, light as to construction and will 75 positively hold rails in such manner that so spreading thereof is obviated.

In practice, I have found that the form of my invention, illustrated in the drawings and referred to in the above description, as the preferred embodiment, is the 85 most efficient and practical; yet realizing that the conditions concurrent with the adoption of my device will necessarily vary, I desire to emphasize the fact that various 80 minor changes in details of construction, proportion and arrangement of parts may be resorted to, when required, without sacrificing any of the advantages of my invention, as set forth.

What is claimed is:—

1. A rail tie consisting of a metallic body portion having a longitudinal slot in its upper face and recesses in the ends on the upper face communicating with the slot of angular stationary rail clamping members mounted within the recesses, movable rail clamping members mounted within the slot and consisting of elongated shanks arranged within the slot and angular rail clamping portions formed on the shanks to engage 100 the rails; the outer ends of said shanks extending within the recesses and engaging upon the stationary rail clamping members, and means carried by the body portion and arranged between the opposed ends of the shanks to move the shanks into adjusted 105 clamping position.

2. A rail tie consisting of a metallic body portion having a longitudinal slot in its upper face and recesses in the ends on the upper face communicating with the slot of angular stationary rail clamping members mounted within the recesses, movable rail clamping members mounted within the slot and consisting of elongated shanks arranged within the slot and angular rail clamping portions formed on the shanks to engage 115 the rails, the outer ends of said shanks extending within the recesses and engaging upon the stationary rail clamping members, means carried by the body portion and arranged between the opposed ends of the shanks to move the shanks into adjusted 120 clamping position, and means to secure the stationary clamping members against up- 125 130

ward movement consisting of lugs carried on the lower ends thereof and said recesses having the inner faces of the outer walls provided with relatively small recesses to receive the said lugs.

5. A rail tie consisting of a body portion having a longitudinal slot in the top thereof and recesses in the ends at the top communicating with the slot, an angular stationary rail clamping jaw mounted within each recess and consisting of a base and an upstanding curved rail engaging portion, rail clamping jaws mounted within the slots consisting of shanks having integral upstanding curved rail clamping portions thereon, the outer ends of said shanks engaging upon the faces of the stationary clamping members, the inner ends of the shanks being spaced and a wedge plate adjustingly mounted between the inner ends of the shanks.

4. A rail tie consisting of a body portion having a longitudinal slot in the top thereof and recesses in the ends at the top communicating with the slot, an angular stationary rail clamping jaw mounted within each recess and consisting of a base and an upstanding curved rail engaging portion, rail clamping jaws mounted within the slots 25 consisting of shanks having integral upstanding curved rail clamping portions thereon, the outer ends of said shanks engaging upon the faces of the stationary clamping members, the inner ends of the shanks being spaced, a wedge plate adjustingly mounted between the inner ends of the shanks, and means to hold the wedge plate in adjusted position, said shanks having their inner opposed ends concaved to receive the sides of the wedge plate and the outer ends of said shanks arranged to be engaged by the bases of the rails and to have the rails rest thereon.

clamping members, the inner ends of the shanks being spaced, a wedge plate adjustingly mounted between the inner ends of the shanks, and means to hold the wedge plate in adjusted position.

5. A rail tie consisting of a body portion having a longitudinal slot in the top thereof and recesses in the ends at the top communicating with the slot, an angular stationary rail clamping jaw mounted within each recess and consisting of a base and an upstanding curved rail engaging portion, rail clamping jaws mounted within the slots consisting of shanks having integral upstanding curved rail clamping portions thereon, the outer ends of said shanks engaging upon the faces of the stationary clamping members, the inner ends of the shanks being spaced, a wedge plate adjustingly mounted between the inner ends of the shanks, and means to hold the wedge plate in adjusted position, said shanks having their inner opposed ends concaved to receive the sides of the wedge plate and the outer ends of said shanks arranged to be engaged by the bases of the rails and to have the rails rest thereon.

In testimony whereof I affix my signature in presence of two witnesses.
